BOX

Elias Wolf, Elkins Park, Pa., assignor to Louis Wolf, Howard A. Wolf, and Elias Wolf, co-partners trading as National Metal Edge Box Company, Philadelphia, Pa.

Application September 28, 1932, Serial No. 635,133

2 Claims. (Cl. 229—52)

This invention relates to a box formed of pasteboard or other semi-rigid material and particularly to a construction of such box having two relatively foldable parts forming an enclosed box of substantial rigidity.

The primary object of the present invention relates to the provision of means whereby a box of the general type indicated above is provided which is locked in its closed position; that is, by the interfitting of parts it is held closed and can only be opened by its partial destruction, unless considerable care is exercised. The box is also provided with a handle related in a novel fashion to the locked means so that the box may be most readily prepared from a simple type of blank.

Further objects relating to details of construction will be apparent from the following description read in conjunction with the accompanying drawings in which:

Figure 1 is a plan view of a blank from which one form of the improved box may be made;

Figure 2 is a perspective view of the upper portion of the box after partial assembly;

Figure 3 is a perspective view of the finished box;

Figure 4 is a plan view showing a modified type of blank for a larger box;

Figure 5 is a perspective view of the upper portion of the modified box prior to complete assembly; and

Figure 6 is a perspective view of the upper portion of the finished modified box.

Referring first to Figures 1-3 inclusive, the box of this modification is formed of a single blank which provides the faces 2 and 4, the bottom 6, the side flaps 8, which in the finished box overlap, and top flaps 10, which in part provide the top wall of the box. These various parts are defined in the blank by scored lines, which permit easy folding when assembly into the finished box takes place.

Carried by the upper end of the wall 4 is a top flap 12, the function of which with the wall 4 consists of a scored line. Undercuts extending inwardly to points 14 separate the ends of the flap 12 from the wall 4.

At the top of the wall 2 and joined thereto along a scored line is a flap 16, which at its ends carries flaps 18 hinged thereto along suitably scored lines. The inner ends of the flaps 18 are beveled as indicated at 20 to the points 22 inwardly of which undercuts 24 extend, separating the points 22 from the body of the flap 16. The central portion 26 of the flap 16 is defined

from the ends thereof preferably by a series of perforations 28 so that finally this central portion of the flap may be turned upwardly to provide a handle, the flap 30, which is separated from 26 along three of its sides, being joined thereto along a scored line 32 so that it may be turned upwardly to provide a convenient grip which will not cut the hand of the carrier. 5

The distance between the points 22 is less than the distance between the inner points 14 10 of the undercuts between the flap 12 and the wall 4. Consequently, when partially assembled, as indicated in Figure 2, substantial pressure must be exerted to cause the flaps 18 to move fully inwardly and contact with the ends 15 of the flap 12. The baffles 20 ride against the inner ends 14 of the undercuts, causing some slight distortion of the parts until the undercuts 24 lock with 14. Following this interengagement of the undercuts, it will be obvious that without 20 careful manipulation the box cannot be opened except by destruction of some of the parts adjacent the interlock.

Up to this time the central portion 26 of the flap may remain undetached from the ends of the flap 16. In this case the closed box is in condition for shipment. When the box is to be carried, tearing is effected along the perforations 28, so that the central portion 26 may be brought to an upright position, as viewed in Figure 3. By 30 turning the flap 30 a suitable opening for the fingers is provided together with a handle having a rounded edge which will facilitate carrying.

In the modification of Figures 4, 5 and 6 the parts corresponding to those of Figure 1 are similarly designated. This box, in fact, differs only from that of Figure 1 in its larger size, which makes desirable a somewhat modified handle arrangement and different relative dimensions of the interlocking arrangement. 35 40

In addition to the flaps 10 associated with the wall 4, there are provided inwardly extending flaps 33 to provide more secure end assemblies; these flaps eventually extending against the wall 4. 45

The flap 16 has the central portion thereof formed as a handle flap 34 defined by undercuts 36 of the character indicated, providing inwardly extending projecting portions 38 from the flap 16 into the opening which appears when the flap 34 is turned upwardly to form a handle, this turning of the flap taking place along scored lines 40. A flap 42, defined by cuts along three sides is adapted to pivot about the scored line 44, forming its junction with the flap 34. 50 55

The top flap 12 carried by the wall 4 is provided with a handle flap 46 defined therefrom by cut 48 formed as shown, to provide projections 50 on the handle flap. The flap 46 folds about 5 scored lines 52 and is provided with an opening 54 corresponding to the flap 42, which may be turned thereover in the finished box.

The assembly so far as the interlocking of the undercuts 24 and 14 is concerned is similar to 10 that of the previous arrangement. In addition, the parts are locked together by the interengagement of the projections 38 and 50, as illustrated in Figure 6. The dimensions are such that the 15 inner corners of the opening, formed by turning upwardly the handle flap 34, are spaced approximately the same distance as the lowermost ends of the side edges of the flap 46; in other words, the distance between the inwardly directed projections 38 is less than the distance between the 20 outer portions of the projections 50. As a result, during assembly some distortion is necessary, but finally the parts assume the relationships illustrated in Figure 6, so that the two flaps are held together to form a unitary handle. Further maintenance of the two handle parts in 25 juxtaposition is secured by the turning of the flap 42 through the opening 54 whereby it not only forms a lock, but a convenient grip.

It will be clear from the above that numerous

variations of the specific form of the invention may be made without departing from the spirit thereof as defined in the following claims.

What I claim and desire to protect by Letters Patent is:

1. A box including two portions one of which overlaps the other to close the box, each of said portions having a flap, said flaps being arranged to assume overlapping relationship when the box is closed, a handle formed by part of one of the flaps, and means whereby the outer flap is locked at the base of the inner flap, said means including slots at the base of the inner flap and members carried by the outer flap engaging within the slots, said members comprising undercut flaps 1 integral with the outer flap.

2. A box including two portions one of which overlaps the other to close the box, each of said portions having a flap, said flaps being arranged to assume overlapping relationship when the box 20 is closed, a handle formed by part of one of the flaps, and means whereby the outer flap is locked to the inner one, said means including members carried by the outer flap having portions engaging the inside of the inner flap, said members 25 comprising undercut flaps integral with the outer flap.

ELIAS WOLF.
